UNITED STATES PATENT OFFICE.

RUDOLPH W. GOEB, OF ST. LOUIS, MISSOURI, ASSIGNOR TO THE CONTROLLER COMPANY OF AMERICA, OF ST. LOUIS, MISSOURI, A CORPORATION OF MISSOURI.

LOCKING MECHANISM.

SPECIFICATION forming part of Letters Patent No. 739,075, dated September 15, 1903.

Application filed October 13, 1902. Serial No. 127,094. (No model.)

To all whom it may concern:

Be it known that I, RUDOLPH W. GOEB, a citizen of the United States, residing at St. Louis, Missouri, have invented a certain new and useful Improvement in Locking Mechanisms, of which the following is a full, clear, and exact description, such as will enable others skilled in the art to which it appertains to make and use the same, reference being had

10 to the accompanying drawings, forming part of this specification, in which—

Figure 1 is an elevation of the present mechanism, the casing being shown in section. Fig. 2 is an elevation at right angles to the view shown in Fig. 1, the greater portion of the front wall of the casing being removed and the front wall of the coin-slot being broken away, while a portion of the casing is shown in section. Fig. 3 is a top plan view, partly in section; and Fig. 4 is a fragmentary detail view.

15 My invention relates to improvements in locking mechanisms, and is particularly applicable to coin-controlled locking mechanisms for telephones.

20 My object is to simplify the construction of that portion of the mechanism which permits the parts to be thrown into unlocking position by an authorized person without the use of a coin or token and to remove any possibility 25 of the mechanism failing to be brought into locking position when the receiver is replaced upon the hook.

To these ends and also to improve generally upon mechanism of the character indicated, my invention consists in the various matters hereinafter described and claimed.

Referring now more particularly to the drawings, 1 indicates a telephone-box of any usual or preferred construction, and 2 the receiver suspension-hook extending from the same, the receiver being indicated as 3. A box or casing 4, suitably supported at the side of the telephone-box, as by being connected 40 to a wall or other support, contains the hereinafter-mentioned locking mechanism and is provided with a coin-slot or raceway 6. The front wall of the casing is provided with a horizontal slot 7, and pivotally supported to 45 rotate through said slot is a spider-plate 8,

having arms 9, these arms successively projecting beyond the casing as the plate is rotated and being spaced from each other a sufficient distance to permit the telephone-receiver 3 to lie between any adjacent arms 55 when the receiver is supported upon the suspension-hook. Pivotally supported within the casing is a locking-lever 10, which has a coin-receiving arm 11, projecting upon one side of the pivot and extending under the 60 raceway 6, and has also a locking-arm 12, which when the parts are in normal position lies slightly above the plane in which the arms of the spider-plate rotate. A finger or projection 13 depends from the free end of 65 the locking-arm 12, and when the said arm is in normal locking position a suitable portion of said finger or projection lies in the path of travel and slightly in advance of one of the arms 9 of the spider-plate or receiver-locking 70 element. The locking-lever is also provided with a stop-arm 14, which extends under the locked arm 9 of the spider-plate and is adapted to engage said arm when the locking-arm of the lever is thrown upwardly and to thus limit 75 the initial movement of the locking-lever, so that said lever will not initially be thrown into such a position that the coin is deposited from the coin-receiving arm 11.

The parts are shown in their normal locking positions in Figs. 1 and 3 and in full lines in Fig. 2. When a coin is deposited into the raceway 6, it falls upon the coin-receiving arm 11 and throws the locking-lever into the position indicated by dotted lines in Fig. 2, 85 and when the receiver is withdrawn from between the arms 2^a of the fork of the receiver suspension-hook the spider-plate is rotated sufficiently to carry the arm 9, which has heretofore been locked out of engagement 90 with the stop-arm 14, and the locking-lever is thus permitted to rotate sufficiently to cause the coin to be discharged. The portion of the locking-lever upon the side of the pivot which includes the locking-arm overbalances the portion of said lever upon the opposite side of its pivot, so that as soon as the coin is discharged the locking-lever falls into its normal position, the free end of the locking-arm being beveled, as shown at 15, to 100

permit a spider-arm to lift the locking-lever and move backwardly under the same as the spider-plate is rotated by the action of replacing the receiver upon the hook 2, the 5 locking-lever falling into locking position as soon as such spider arm 9 has passed backwardly under the finger or projection 13.

The mechanism heretofore described forms no part of my invention and is fully disclosed 10 in the application of William H. Scott for patent upon telephone-lock, filed September 6, 1902, Serial No. 122,392. It is believed that no further explanation of the operation of the above-described mechanism is necessary 15 in this specification.

Suitably supported within the casing 4, and preferably below the locking-lever 10, is an electromagnet 16, and a releasing-lever 18, which has an armature 17 formed thereon or 20 attached thereto, is pivotally supported in the casing to coöperate with the said magnet, the said releasing-lever being preferably pivoted below the said magnet and extending upwardly, so that its upper end (or a laterally-extending finger 18^a thereon) lies under and is adapted to coöperate with the lower edge 14^a of the stop-arm 14. The releasing-lever is so pivoted that it tends to fall away from the magnet 16, the outward movement 25 of said lever being conveniently limited by causing the free end of the lever to extend at the side of the locking-arm 12, as shown at 18^b, said releasing-lever (or the extension 18^b thereof) being of such length that in the outward movement of the lever the said extension 30 engages the stud 45, upon which the locking-lever 10 is pivoted.

The projection or finger 13 forms what may be termed a "locking-shoulder" 13^a with the 35 locking-arm 12, which locking-shoulder is a portion of the said finger which lies in advance of one of the spider-arms 9 for locking said arm against forward movement, and from the lower end of said locking-shoulder 40 the said projection 13 is beveled downwardly and outwardly, as shown at 13^b, this beveled surface meeting the beveled end 15 in a point. At the outer end of the surface 14^a of the stop-arm which coöperates with the finger 18^a 45 is a notch 14^b, which is adapted to receive the said finger 18^a, the parts being so proportioned that when the releasing-lever 18 is in normal position, as shown by full lines in Fig. 2, the locking-arm of the locking-lever lies 50 in such position that the locking-shoulder 13^a is in advance of one of the spider-arms 9 and the spider-plate is locked, as heretofore described, while when the releasing-lever 18 is in its raised position, to which it is brought 55 when attracted by the magnet, the finger 18^a lies in the notch 14^b and the locking-arm 12 is elevated to such an extent that the locking-shoulder 13^a lies above the spider-plate.

The magnet 16 is included in an electric 60 circuit which is provided with a push-button or other switch, which can be located at any convenient point. When the circuit is

open, the parts lie in the positions indicated by full lines in Fig. 2 and the spider-plate is locked against forward rotation. When, however, the circuit is closed, the releasing-lever 18 is attracted to the magnet, and as the surface 14^a intersects the arc in which the engaging edge of the finger 18^a moves the said finger 18^a rides upon the said surface during 70 its movement to elevated position, and the locking-lever is thus rocked to elevate its locking-arm, the said locking-lever rocking backwardly slightly when the said finger 18^a passes beyond the said surface 14^a in order 75 to cause the said finger 18^a to lie in the notch 14^b, and thus support the locking-lever in rocked position, with the locking-shoulder 13^a above the plane of the spider-plate 8, as shown in dotted lines in Fig. 4. The spider-plate 85 is now free to be rotated in either direction, and as the receiver is withdrawn from the hook it engages one of the spider-arms 9, and thus rotates the spider-plate to cause the spider-arm 9, which has heretofore been 90 locked, to engage the beveled surface 13^b of the projection or finger 13 and to thereby rock the locking-lever to elevate the stop-arm 14 sufficiently to free the finger 18^a of the releasing-lever from the notch 14^b, as shown in 95 dotted lines in Fig. 4, whereupon, the circuit being broken, the releasing-lever falls into normal inoperative position, as shown by dotted lines in Fig. 4 and by full lines in Fig. 2, and the locking-lever 10 returns to its normal 100 position, ready to lock an arm of the spider-plate when the same is forced backwardly beneath the finger 13 as the receiver is replaced upon the hook.

As will be apparent from the foregoing description, the spider-plate is returned to locked position by having one of its arms thrown backwardly under the finger or projection 13, the locking-arm 12 being thrown upwardly by reason of the engagement of the 105 spider-arm with the beveled lever end 15. As the locking-arm 12 rises the stop-arm 14 also rises, and should the spider-arm 9 be forcibly and rapidly thrown backwardly there is some little danger of the said arm 9 meeting the stop-arm during the backward movement of the spider-arm. If, therefore, the end 110 of the stop-arm were substantially vertical and were thus to meet the vertical edge of the spider-arm, there is danger of the stop-arm preventing the spider-arm from completing its full backward movement, in which event the spider-arm could come to rest directly under the projection 13, with said projection supported upon said arm and the 115 parts thus in unlocked position. In order to avoid this possibility, I have beveled the free end of the stop-arm upwardly and backwardly, as shown at 14^c, whereby even if the end of said stop-arm should be struck by the 120 spider-arm as the latter moves toward locked position the said spider-arm merely rides along the said beveled surface of the stop-arm, and thus forces said stop-arm out of the way.

The releasing mechanism is extremely simple and adds only two parts to the machine—namely, the electromagnet and the releasing lever.

5 I am aware that many minor changes in the construction, arrangement, and combination of the several parts of my device can be made and substituted for those herein shown and described without in the least departing from 10 the nature and principle of my invention.

Having thus described my invention, what I claim, and desire to secure by Letters Patent, is—

1. In a mechanism of the character indicated, a lockable element, a movable locking member for locking the same, a movable releasing member whose tendency is to move from releasing position, means whereby said releasing member supports said locking member in unlocking position, means for maintaining said releasing member in releasing position, and means whereby said releasing member moves from releasing position upon movement of said lockable element; substantially as described.

2. In a mechanism of the character indicated, a movable locking member, a movable releasing member, means whereby said releasing member supports said locking member in unlocking position, and means whereby said locking member supports said releasing member in releasing position; substantially as described.

3. In a mechanism of the character indicated, a lockable element, a movable locking member therefor, a movable releasing member, means whereby said releasing member supports said locking member in unlocking position, means whereby said locking member supports said releasing member in releasing position, and means whereby upon movement of said lockable element said releasing member is thrown from said releasing position; substantially as described.

4. In a mechanism of the character indicated, a lockable element, a movable locking member therefor, a movable releasing member, means whereby said releasing member supports said locking member in unlocking position, means whereby said locking member supports said releasing member in releasing position, and a part upon said locking member and in the path of movement of said lockable element, whereby upon movement

50 of said lockable element said locking member is thrown from supporting position; substantially as described.

5. In a mechanism of the character indicated, a lockable element, a movable locking member therefor, a projection upon said locking member and having a locking shoulder and an inclined surface adapted to lie in the path of movement of said lockable element when said member is in unlocking position, a movable releasing member, means whereby said releasing member supports said locking member in unlocking position, and means

whereby said locking member supports said releasing member in releasing position; substantially as described.

70

6. In a mechanism of the character indicated, a lockable element, a movable locking member therefor provided with a notch, a movable releasing member having a part adapted to enter said notch, whereby said releasing member is maintained in releasing position, and means whereby when said lockable element is moved said locking member is moved to release said releasing member; substantially as described.

75

7. In a mechanism of the character indicated, a movable locking member, a movable releasing member coöperating therewith, and a supporting device for said locking member and in the path of movement of said releasing member to limit such movement; substantially as described.

85

8. In a mechanism of the character indicated, a lockable part, a movable locking member having a locking-arm and a stop-arm, said stop-arm being provided with a notch, a movable releasing member having a part adapted to enter said notch, and a projection upon said locking-arm provided with a locking-shoulder and a surface adapted to be engaged by said lockable part in the movement of the latter for causing said locking member to be thrown to release said releasing member from said notch; substantially as described.

90

9. In a mechanism of the character indicated, a lockable element, a movable locking member including a locking-arm and a stop-arm, said stop-arm being adapted to engage said lockable element in the movement of said locking member by which said lockable element is released, and means whereby said lockable element throws said locking member when said element engages said stop-arm; substantially as described.

100

10. In a mechanism of the character indicated, a lockable element, and a movable locking member provided with a locking-arm and a stop-arm, said stop-arm being adapted to engage said lockable element in the movement of said locking member by which said lockable element is released and having movement across the path of movement of said lockable element, and one of said two last-mentioned parts having an inclined surface presented to the other thereof; substantially as described.

110

11. In a mechanism of the character indicated, a lockable element, and a movable locking member having a locking-arm and a stop-arm, said stop-arm being adapted to engage said lockable element in the movement of said locking member by which said lockable element is released, the end of said stop-arm being inclined; substantially as described.

115

12. In a mechanism of the character indicated, a lockable element, a movable locking member having a locking-arm and a stop-arm, each of said arms being movable across the path of movement of said lockable ele-

120

125

130

- ment, means whereby said lockable element can engage said locking-arm and thus move said locking member in a direction tending to throw said stop-arm across the path of movement of said lockable element, and means whereby when said lockable element engages said stop-arm in its said movement it throws said stop-arm out of said path of movement; substantially as described.
13. In a mechanism of the character indicated, a lockable element, and a movable locking member having a locking-arm and a stop-arm, each of said arms being movable

across the path of movement of said lockable element and each of said arms having an inclined surface adapted to be engaged by said lockable element during its movement in the said path; substantially as described.

In testimony whereof I hereunto affix my signature, in the presence of two witnesses, this 9th day of October, 1902.

RUDOLPH W. GOEB.
